CLAIM

The ornamental design for a steering wheel, or the like, substantially as shown and described.

DESCRIPTION

FIG. 1 is a top plan view of the steering wheel, or the like, showing my new design.

FIG. 2 is a front elevational view thereof;

FIG. 3 is a rear elevational view thereof;

FIG. 4 is a side elevational view thereof, the opposite side being a mirror image of that shown; and

FIG. 5 is a bottom plan view thereof.

FIG. 1.

FIG. 2.

FIG. 3.

FIG. 4.

FIG. 5.
